[57] CLAIM

The ornamental design for a cap, as shown and described.

DESCRIPTION

FIG. 1 is a perspective view of a cap showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof, with the interior of the cap shown in broken lines and forming no part of the claimed design; and,

FIG. 8 is a perspective view of the cap, with the broken line showing of a bottle being for illustrative purposes only and forming no part of the claimed design.
